HEATING APPARATUS

Walter Gilroy, Freeport, N. Y.

Application March 18, 1936, Serial No. 69,448

5 Claims. (Cl. 257—248)

This invention relates to heating apparatus and particularly to a steam generator or liquid heater to be used in an oil or gas burning heater, particularly one of the home heating type which has been changed from the coal burning type to oil or gas burning type.

Where a change of the above type is made, it generally happens that the construction of the boiler is such that while the heating surfaces are properly designed when coal or other solid fuel is used, they are generally relatively inefficient when oil or gas is used as the fuel. In accordance with the present invention there is provided an auxiliary element designed to be located in the fire-box and to receive water from the boiler or heater or, alternatively, from the return connections prior to entrance of the water into the boiler. The invention is applicable to the hot water type of heating system as well as steam or vapor heating systems. For convenience, however, instead of referring to the alternatives, reference will be made to the auxiliary device as a steam generator and in general to a steam heating system, though it will be understood that a hot water or vapor heating system may be involved instead. The invention is also applicable to other than household or building heating systems and may be used for the generation of moderate amounts of steam or hot water for other purposes.

The device is so arranged as to make the maximum use of the heating powers of the products of combustion and to this extent is designed not only to present a maximum surface to the products of combustion but also to present a maximum surface with which the liquid to be heated or boiled may contact to secure rapid and efficient heat transfer.

Besides the general objects above, other objects of the invention relate primarily to details of construction and will become apparent from the following description read in conjunction with the accompanying drawings, in which:

Fig. 1 is a diagrammatic elevation partly in section showing a boiler and connections thereto with which the improved device is associated;

Fig. 2 is a similar view showing a modified arrangement of the improved device in connection with a boiler;

Fig. 3 is a vertical section through the device;

Fig. 4 is a horizontal section taken on the plane indicated at 4—4 in Fig. 3; and

Fig. 5 is a horizontal section taken on the plane indicated at 5—5 in Fig. 3.

Referring first to the device, which will be

referred to as a steam generator with the understanding indicated above of its broader application, this steam generator is illustrated in detail in Figs. 3, 4 and 5. It comprises a lower liquid inlet chamber 2 which is of generally symmetrical form and which is provided with a tapped inlet opening 4 and a tapped outlet opening 6. Horizontal baffles 8 and 10 are arranged transversely of the chamber 2 and are provided with openings 12 and 14 which are misaligned, as indicated in Fig. 3, so that the liquid flowing upwardly through the chamber has imparted to it a zigzag course prior to reaching the opening 6. A sediment clean-out plug 16 may be provided in the bottom of this chamber.

The chamber 2 is connected through a pipe nipple 18 tapped into the opening 6 with an intermediate chamber 22 which is provided with a tapped opening 20 receiving the nipple. The chamber 22 is of the form indicated in Figs. 3 and 4 and is provided with a cavity indicated at 24 through which the products of combustion may circulate upwardly for engagement with the upper chamber. This intermediate chamber is also provided with a vertical opening 26 to additionally provide for circulation of the products of combustion and contains baffles 28 which prevent direct passage of the liquid from the entrance opening 20 to the exit opening 30.

A pipe nipple 32 is tapped into the opening 30 and also into an opening 34 of the upper chamber 36. This chamber, which is illustrated in Figs. 3 and 5, is provided with a dished under surface adapted to entrap the products of combustion and produce a turbulence to promote circulation about the intermediate chamber 22. This upper chamber is provided with baffles 38 and 40 arranged as indicated in Fig. 5, which provide a devious course for the liquid from the entrance opening 34 to the exit opening 42. An alternative exit opening 44 may be provided for convenience in making connections, though in the arrangements indicated this latter opening is plugged, the exit of liquid being from the opening 42.

When the arrangement just described is located within a boiler 46 as indicated in Figs. 1 and 2, above an oil or gas burner indicated at 48, it will be obvious that the products of combustion will flow up about the lower chamber 2 and thence about the intermediate chamber through the concavity 24 and the opening 26 to impinge upon the concave lower face of the upper chamber 36. From about this upper chamber the

products will pass in contact with the conventional heating surfaces of the boiler indicated in Fig. 1 and thence to the flue.

The steam outlet of the boiler is indicated at 5 50, while the return water connection is indicated at 52. The return occurs into the water jacket 54 of the fire-box, which extends downwardly from the dome 56.

Referring first to Fig. 1, there is shown therein 10 one arrangement for connecting the generator into the boiler, this arrangement being particularly adapted for the generation of steam. The lower chamber 2 is connected, through a pipe 58 secured in the walls of the boiler and connecting 15 pipe 60, with the return connection 52. The outlet of the upper chamber 36 is connected by means of a pipe 62 with a separator 64, connections being made at both 66 and 68, the former primarily serving for the flow of water and the 20 other for the flow of steam. A connection 70 at the upper end of the separator 64 provides communication between it and the steam pipe 50.

72 represents the return for the water separated in 64 and may be connected, for example, 25 to the junction of the pipes 58 and 60. A check valve 74 is interposed in the connection 72 to prevent the reverse flow of water upwardly therethrough. Additionally a globe valve 76 may be provided to cut off this connection when that is 30 desirable.

A connection 78 may be provided between the pipe 62 and the dome 56 of the boiler, this connection being provided with a valve 80 while the pipe 62 is provided with a valve 82 thereabove.

Assuming that the valves 76 and 82 are opened 35 and that the valve 80 is closed, steam and water will pass upwardly through the pipe 62 into the separator, from which the steam will flow through 40 70 to the main steam pipe 50 and the separated water will return through pipe 72 and check valve 74. If desired, the valve 80 may be open at this time, providing for flow of water and steam into the dome. Alternatively, valves 76 and 82 may be closed and valve 80 opened, in which case the 45 separator is taken entirely out of the system and the steam and water from the upper chamber 36 of the generator flow directly into the dome. This arrangement may, of course, be also achieved by omitting the connections to the separator.

50 A simple arrangement is indicated in Fig. 2. In this case the generator is connected directly with the water jacket 54 of the fire-box by means of pipes 84 and 86. In such case the steam generated will flow directly into the dome from 55 the jacket.

While the generation of steam has been primarily referred to, it will be obvious that the arrangement may be used for the heating of water. In such case, of course, there is no necessity for using a separator. Steam may be generated, nevertheless, in the three chambers but by its condensation may merely heat the water.

It will be clear that numerous variations may be made in the embodiment of the invention without departing from the scope of the claims.

What I claim and desire to protect by Letters Patent is:

1. Apparatus for the heating of liquid designed for arrangement within the combustion space of a heater comprising a plurality of chambers, means for connecting said chambers to provide a flow of liquid therebetween, means for leading liquid to the chambers, means for providing an exit of liquid from the chambers, and baffles within the chambers for producing a zigzag flow of liquid therethrough, one of said chambers having a passage for flow of gases therethrough. 10

2. Apparatus for the heating of liquid designed for arrangement within the combustion space of a heater comprising a plurality of chambers, means for connecting said chambers to provide a flow of liquid therebetween, means for leading liquid to the chambers, means for providing an exit of liquid from the chambers, and baffles within the chambers for producing a zigzag flow of liquid therethrough, one of said chambers having a concave lower wall to receive upwardly flowing gases. 15

3. Apparatus for the heating of liquid designed for arrangement within the combustion space of a heater comprising a plurality of chambers, means for connecting said chambers to provide a flow of liquid therebetween, means for leading liquid to the chambers, means for providing an exit of liquid from the chambers, and baffles within the chambers for producing a zigzag flow of liquid therethrough, one of said chambers having a passage for flow of gases therethrough, and another chamber being arranged above the last named chamber and being provided with a concave lower wall to receive upwardly flowing gases. 25

4. Apparatus for the heating of liquid designed for arrangement within the combustion space of a heater comprising a plurality of superimposed chambers, means for connecting said chambers to provide a flow of liquid therebetween, means for leading liquid to the chambers, and means for providing an exit to liquid from the chambers, said chambers including an intermediate one of crescent shape having a passage for flow of gases upwardly therethrough, and a chamber above said crescent shaped chamber provided with a concave lower wall to receive gases flowing upwardly through the passage in the crescent shaped chamber. 30

5. Apparatus for the heating of liquid designed for arrangement within the combustion space of a heater comprising a plurality of superimposed chambers, means for connecting said chambers to provide a flow of liquid therebetween, means for leading liquid to the chambers, and means for providing an exit to liquid from the chambers, said chambers including an intermediate one of crescent shape having a passage for flow of gases upwardly therethrough, and a chamber above said crescent shaped chamber provided with a concave lower wall to receive gases flowing upwardly through the passage in the crescent shaped chamber, said chambers being provided with interior baffles producing a zigzag flow of liquid therethrough. 40
